UNITED STATES PATENT OFFICE

HAROLD ALBERT WHITE, OF AYLMER, ONTARIO, CANADA

PENCIL

Application filed November 7, 1929. Serial No. 405,430.

This invention relates to a mechanical pencil of a type in which a propelling mechanism is employed for projecting the marking lead beyond, or, retracting it within, the pencil, and according to my present improvements the invention is characterized in that the pencil comprises, a tubular casing provided with a spring tensioned tip which recedes relatively to the casing when pressure is applied to it for overcoming the spring tension and advances when the pressure is released, a lead holder and a propelling mechanism for the lead holder actuated by the tip at each complete cycle of its receding and advancing movements for a step by step progression of the lead holder through the casing towards the tip. The invention is further characterized in that pressure actuated means are provided for actuating the propelling mechanism to retract the lead within the casing.

For an understanding of the invention reference is to be had to the following description and to the accompanying drawing, in which:

Fig. 1 is a longitudinal section of a mechanical pencil constructed according to this invention;

Fig. 2 is a fragmentary longitudinal section showing a modification of the propelling means;

Fig. 3 is a cross section on a line 3-3, Fig. 2;

Fig. 4 is a fragmentary longitudinal section showing a further modification of the propelling mechanism;

Fig. 5 is a cross section on a line 5-5, Fig. 4.

Like characters of reference refer to like parts throughout the specification and drawing.

The pencil shown in Fig. 1 comprises a tubular casing 1, provided with an axial bore 3 extending inwardly from its tip end, and a counter bore 4 extending from the bore 3 to its head. The casing is provided with an axially movable tip 2, which protrudes beyond the end of the casing and is constructed with a tubular sleeve 5. The tubular sleeve 5 is entered in the bore 3 and

counter bore 4, and, provided, intermediate its ends, with a peripheral shoulder 6 which engages the shoulder 7 at the junction of the bore and counter bore for limiting the outward movement of the sleeve and tip. Formed through the pointed end of the sleeve or tip is a bore 9 of corresponding diametric dimension to the marking lead, and extending from the inner end of the bore 9 to the inner end of the tubular sleeve 5 is a counter bore 10 of corresponding diametric dimension to the lead holder 11. Adjustable within the tubular casing 1 is a barrel 12, extending from the head towards the tip end of the casing and overlapping the inner end of the sleeve 5. Coiled on the sleeve 5 and abutting against the shoulder 6 and the adjacent end of the barrel 12 is a spring 13 for advancing the sleeve and tip relatively to the casing until arrested by the engagement of the peripheral shoulder 6 with the shoulder 7, the tip receding relatively to the casing when sufficient pressure is applied to it for compressing the spring 13, and advancing again when the pressure is released.

Within the barrel is an axially movable rack 14 comprising part of the propelling mechanism, and connected with the rack 14 is a lead holder 11. The rack meshes with and is actuated by a gear wheel 16 mounted on a stud 17 in the bore of the barrel 12, and, during the rotation of the gear wheel in a clockwise direction, advances towards the sleeve for a step by step progression of the lead holder through the casing, for protruding, at each step of the progression, a predetermined length of lead beyond the point of the tip. The rack, during the rotation of the gear wheel in a counter clockwise direction, recedes towards the head of the pencil and retracts the lead within the point of the tip. Secured to the side face of the gear wheel 16 is a ratchet wheel 18, the diameter of which is less than that of the gear wheel. Connected to the inner end of the sleeve 5 is a ratchet lever 19 which meshes with the teeth of the ratchet wheel 18 during the advancing movement of the sleeve for causing the rotation of the ratchet wheel 18

and the gear wheel 16 in a clockwise direction, and slides over the teeth of the ratchet wheel, without imparting motion to it, during the receding movement of the sleeve. 5 The barrel 12, at or near the head of the casing, is provided with a slot 20 elongated lengthwise of the barrel, and the head of the casing is provided with a cap 21 having a core 22 entered in the barrel and overlapping the slot. Extending from the core 22 is a pin or stop 23 entered in the slot 20 for engaging the ends of the slot and limiting the movements of the cap. Within the bore 10 of the barrel is an abutment 24, and seated against the abutment and the inner surface of the cap is a spring 25 which normally presses the cap outward until its movement is arrested by the engagement of the stop 23 with the outer end of the slot 20. Connected with the core 22 is an arm 26 extending from the cap in the direction of the gear and ratchet wheels, and at the inner end of the arm 26 is an inclined face 27 opposed to the ratchet lever 19. Pivoted to the arm 25 26 is a pawl 28 which engages the teeth of the gear wheel 16 when the cap is pressed inwards, and which becomes disengaged from the gear wheel when the cap moves outwards to its normal spring pressed position. 30 The pawl 28 is held in the position shown by a spring which holds it against the teeth of the ratchet wheel 18 when the arm 26 moves downwardly and permits it to slide over the teeth when the arm 26 is moved upwardly. A releasing pawl 29 is pivoted between the arm 26 and the ratchet lever 19, and one side of the pawl 29 has an inclined face 30 engaged by the inclined face 27 when the arm 26 moves towards the gear wheel 16 for moving the pawl 29 against the ratchet lever and disengaging it from the ratchet wheel. When the arm 26 moves away from the gear wheel 16 the 40 pressure on the face of the pawl 29 is removed, and being free-swinging is returned to its normal position by the resiliency of the ratchet lever 19. At the upper end of the rack 14 is a friction band 31 which engages the inner surface of the barrel and 45 prevents the inadvertent movement of the rack axially of the pencil. 50

For feeding the marking lead through the pencil sufficient pressure is applied to the tip for causing it to recede relatively to the casing and move the ratchet lever 19 in the direction of the cap 21, the teeth of the ratchet lever during this movement sliding past the teeth of the ratchet wheel 18 without causing its rotation in either a clockwise or counter clockwise direction, and the receding movement of the tip being limited only by the compression of the spring 13. When the pressure is released, the spring advances the tip until the peripheral shoulder 6 engages the shoulder 7 and arrests the advance- 60

ing movement. During the advancing movement of the sleeve the teeth of the ratchet lever 19 engage the teeth of the ratchet wheel 18 and rotate it in a clockwise direction. The ratchet wheel, is secured to the gear wheel 16, and imparts to it a corresponding rotation. The gear wheel when rotating in a clockwise direction advances the rack towards the sleeve and pencil tip and a corresponding movement of the marking lead through the bore of the tip. The diameter of the gear wheel 16 being greater than the diameter of the ratchet wheel 18, the teeth of the gear wheel move over a longer arc than those of the ratchet wheel 80 and impart a longer movement to the rack. For example, if the ratio of the diameter of the gear wheel 16 to the diameter of the ratchet wheel 18 is two to one and the movement of the tip is one-sixteenth of an inch, the travel of the tip, during the advancing movement will approximate one-sixteenth of an inch and the travel of the rack, lead holder and marking lead approximate one-eighth of an inch, consequently if the point of the lead is in the same plane as the point of the tip at the commencement of the receding movement the marking lead will be projected one-eighth of an inch beyond the tip at the completion of its advancing movement. 90

The feed of the marking lead through the pencil tip is regulated by the adjustment of the barrel 12 in the casing, that is to say, when the barrel is adjusted towards the shoulder 7 the length of movement of the tip is less than when the barrel is adjusted away from the shoulder. For retracting the lead the cap 21 is pressed inwards and during its inward movement the inclined face 27 of the arm 26 engages the inclined face 30 of the releasing pawl 29 and forces the releasing pawl into engagement with a ratchet lever 19 and displaces the latter from its normal position for disengaging its teeth from the teeth of the ratchet wheel 18 to permit of the free revolution of the ratchet wheel 16 in a counter clockwise direction. The continued movement of the cap forces the arm 26 in the direction of the gear wheel 16 and brings the pawl 28 into engagement with its teeth and causes the revolution of the gear wheel 16 in a counter clockwise direction. The teeth of the gear wheel, being continually in mesh with the teeth of the rack 14, moves the rack, lead holder and marking lead towards the head of the casing during its counter clockwise rotation, thus retracting the marking lead within the pencil tip. 110

In the construction shown in Figs. 2 and 3 a compound lever mechanism is provided for actuating the rack. This lever mechanism comprises a ratchet arm 32 the teeth of which are normally in mesh with the 120

teeth of the ratchet wheel 18; an arm 33 fulcrumed at one end to a lug 34 in the barrel 12 and knuckled at the other end to the arm 32, and a link 35, connected with the arm 33 interjacent the fulcrum 34 and the arm 32 and with the inner end of the sleeve 5.

In the construction shown in Fig. 4 the rack, ratchet wheel and gear wheel are dispensed with and the lead holder 36 is provided with ratchet teeth 37 actuated by a compound lever comprising a ratchet arm 38 engaging the ratchet teeth 37; an arm 39 fulcrumed to a lug 40 within the barrel and knuckled to the ratchet arm 38, and a link 41 is connected with the inner end of the sleeve and the arm 39 interjacent its fulcrum and its knuckle connection with the ratchet arm 38. Springs 42 and 43 bear against the lead holder 36 and ratchet arm 38, respectively, to maintain the teeth of the ratchet arm 38 normally in engagement with the ratchet teeth 37. In the same construction the cap is provided with an arm 44 having a bevelled face 45 which engages with a correspondingly bevelled face 46 at the head of the ratchet arm 38 for displacing the ratchet arm from the ratchet teeth 37 when the lead holder and marking lead are to be retracted within the pencil tip, which, for instance, may be effected by pressing upon the point of the lead and forcing it back into the bore of the tip when the ratchet arm is displaced.

Having thus fully described my invention, what I claim as new and desire to secure by Letters Patent is:—

1. A mechanical pencil comprising a casing provided with a spring pressed pencil tip, which recedes when sufficient pressure is applied to it for overcoming the spring pressure and which advances when the pressure is released, and a propelling mechanism for the marking lead actuated by the pencil tip at each complete cycle of its receding and advancing movements for advancing the propeller mechanism a greater distance than the advancing movement of the pencil tip and projecting a predetermined length of marking lead beyond it.

2. A mechanical pencil comprising a tubular casing having a spring pressed pencil tip which recedes relatively to the casing when pressure is applied for overcoming the spring pressure and advances when the pressure is released, a lead holder, a propelling mechanism for the lead holder, and operable means actuated by the pencil tip at each complete cycle of its receding and advancing movements for advancing the lead holder a greater distance than the advancing movement of the pencil tip and projecting a predetermined length of marking lead beyond it.

3. A mechanical pencil as claimed in claim 1 provided with means for actuating the

propelling mechanism to retract the lead within the casing.

4. A mechanical pencil as claimed in claim 1 comprising a pencil tip provided with a sleeve slidable axially of the casing, a rack for the lead holder, and actuating means operably connected with the sleeve for advancing the lead holder and rack step by step, through the casing, in the direction of the tip.

5. A mechanical pencil as claimed in claim 1 in which the propelling mechanism comprises a rack for the lead holder, a ratchet wheel, a gear wheel meshing with the rack, unitedly rotatable with the ratchet wheel, and a ratchet lever connected with the pencil tip for rotating the ratchet and gear wheels and effecting a step by step progression of the rack and lead holder through the casing in the direction of the pencil tip.

6. A mechanical pencil as claimed in claim 1 in which the propelling mechanism comprises a rack for the lead holder, a ratchet wheel, a gear wheel meshing with the rack unitedly rotatable with the ratchet wheel, a ratchet lever connected with the pencil tip for rotating the ratchet and gear wheels and effecting a step by step progression of the rack and lead holder through the casing in the direction of the pencil tip, and means for displacing the ratchet lever from the ratchet wheel for the retraction of the lead within the pencil.

7. A mechanical pencil as claimed in claim 1 in which the propelling mechanism comprises a rack for the lead holder, a ratchet wheel, a gear wheel meshing with the rack unitedly rotatable with the ratchet wheel, a ratchet lever connected with the pencil tip for rotating the ratchet and gear wheels and effecting a step by step progression of the rack and lead holder through the casing in the direction of the pencil tip, and means for displacing the ratchet lever from the ratchet wheel for the retraction of the lead within the pencil, consisting of a spring pressed cap for the casing having an arm extending in the direction of the ratchet and gear wheels, provided with an inclined face and a pivoted pawl having an inclined face engaged by that of the arm.

8. A mechanical pencil as claimed in claim 1 in which the propelling mechanism is provided with friction means which prevents the inadvertent movement of the rack axially of the pencil.

9. A mechanical pencil as claimed in claim 1 comprising a pencil tip provided with a shouldered sleeve slidable axially of the casing, a barrel within the casing, a spring coiled on the sleeve between its shoulder and the adjacent end of the barrel, a rack for the lead holder, a ratchet wheel, a gear wheel meshing with the rack unitedly rotatable with the ratchet wheel, and a ratchet

lever connected with the sleeve for rotating the ratchet and gear wheels and effecting a step by step progression of the rack and lead holder in the direction of the tip.

- 5 10. A mechanical pencil comprising a casing, a lead holder movable axially within the casing, a spring pressed pencil tip for the casing receding into it when pressure is applied for overcoming the pressure, and
10 means actuated by the pencil tip for advancing the lead holder a greater distance than the progressive movement of the pencil tip at each complete cycle of movement of the latter.
- 15 11. In a mechanical pencil as claimed in claim 10 a gear wheel and a ratchet wheel, unitedly rotatable, and corresponding racks for actuating the lead holder and advancing it at each complete cycle of movement a greater distance than the distance travelled by the pencil tip.
- 20 12. In a mechanical pencil as claimed in claim 10 means for selectively increasing or decreasing the travel of the pencil tip and
25 determining the distance the lead holder travels during its advancing movement and the length of marking lead projected beyond the pencil tip when the advancing movement is completed.
- 30 13. In a mechanical pencil as claimed in claim 10 differential gears for causing the united movement of the lead holder and the pencil tip, said gears advancing the lead holder during the advancing movement of
35 the pencil tip for a greater distance than the latter and during the receding movement of the pencil tip under pressure permitting the lead holder to remain inactive.
- 40 14. A mechanical pencil comprising a casing having a spring pressed pencil tip which recedes into the casing when pressure is applied to it for overcoming the pressure and returns again to its advanced position when the pressure is removed, a lead holder within and movable axially of the pencil casing, operable means actuated by the pencil tip during its advancing movement for advancing the lead holder a distance greater
45 than that of the said tip for projecting the lead beyond the latter in its advanced position, said operable means being inactive when pressure is applied to the pencil tip for its receding movement.
- 50 55 Dated at Toronto, Ontario, the fifth day of October, 1929.

HAROLD ALBERT WHITE.
